THERMAL ADDITIVE WATERFLOODING METHOD

Carl E. Johnson, Jr., Laguna Beach, and Allan P. Tudge, Fullerton, Calif., assignors to California Research Corporation, San Francisco, Calif., a corporation of Delaware

Filed Feb. 19, 1964, Ser. No. 346,008
9 Claims. (CL 166—11)

The present application is a continuation-in-part of application Serial No. 59,655, filed September 30, 1960, now abandoned.

This invention relates to improved methods of assisting the recovery of oil from oil-bearing formations, and more particularly, it relates to methods of using heat to improve the efficiency of assisted recovery when additives are used in the flooding fluid.

In most oil-bearing formations, oil is first recovered by making use of natural formation pressures to move the oil towards producing wells where it may be raised to the surface. After the natural formation pressure has been depleted so it is no longer effective in producing oil, various secondary recovery methods are utilized. It is in this general area that the method of the present invention is concerned, although it is preferred to use the term "assisted recovery" which, while including secondary recovery as known in the art, is not limited to secondary recovery, but may also include primary or tertiary, etc. development of the formation.

The most widely employed method of assisted recovery is water flooding. However, even after a successful water flood, it is often found that 30% to 50% of the original crude oil remains in the formation. Efforts have been made to increase the amount of oil recovered by mixing additives with the flood water. Included under the general term of additives are surface active agents including cationics, nonionics, anionics and ampholytes; water thickeners; bactericides; chemical tracers; and other additives to a water flood used in aiding oil recovery. The usual method of additive flooding involves injecting an amount of additive solution into a formation through one or more injection wells to establish a bank or zone of additive solution in the formation and then, following the injection of additive, injecting untreated water to move the additive solution through the formation while recovering oil at one or more recovery wells.

Many problems, however, have retarded the use of additives in assisted recovery. In order to make additive flooding economically feasible, it is obviously necessary that the value of the incremental oil recovered be greater than the additional cost of the additive flood. A number of factors inherent in additive flooding heretofore have raised the cost of an additive flood so that its use has been prohibitive. Additives are generally complex organic compounds which must be manufactured, thereby making their initial cost high. To compound the problem of the initial cost, most of the additives are strongly adsorbed at the internal surfaces of porous formation rock and, as a consequence, a large amount of additive must be used initially in order to make up the additive temporarily lost by adsorption. The action of adsorption not only removes the additive from solution temporarily, but also causes the additive to become more spread out or dispersed in the formation as it is transported across the formation by the carrier water. Thus, if an additive bank of high concentration is formed in a formation, the action of adsorption quickly reduces the concentration to a lower value. Therefore, unless a very large amount of additive is injected initially, the concentration will soon be so low the additive flood will recover no more oil than

2

a conventional water flood. In addition, because of adsorption, the concentration profile of additive in solution will not travel through the formation as quickly as the water flood, thus resulting in an increase in the amount of flood water that must be injected into the formation in order to carry the additive across the formation to the producing well, and also an increase in the time before any additional oil, due to the additive flood, is recovered.

To better appreciate the present invention, it is necessary to understand the adsorption problem encountered in an additive flood. In any given additive flood, an additive solution of a predetermined concentration is injected into a formation to set up a zone or bank of additive solution. This zone is initially at a concentration which will recover more oil than a conventional water flood. Following the injection of the additive solution, water is injected into the formation to move the additive bank toward a producing well. Since almost all additives are subject to adsorption at solid surfaces, the additive will tend to adsorb at the porous formation as the additive bank is pushed through the formation. This adsorption is in most cases rapid and reversible and tends to reach equilibrium for given conditions of concentration and temperature in a given formation. Therefore, as the bank moves through the formation, additive will be adsorbed from the bank and subsequently desorbed by the following fresh drive water. The end effect of this process is to spread out the additive bank and to eventually reduce the additive concentration in the additive bank to a concentration that will recover no more oil than a conventional water flood. If enough flushing water is forced through the formation, eventually most of the additive can be desorbed and moved through the formation. However, the solution is so dilute that the beneficial effect of the additive flood is lost. It is possible to combat the progressive deterioration of the additive in the bank by injecting a large amount of additive solution so that the additive in the bank will remain at a high concentration through substantially the entire reservoir, however, this is not done due to the prohibitive economics.

Briefly, the present invention provides a method of maintaining, substantially through the entire reservoir, at least a desired minimum concentration of additive in solution in the additive bank which involves generally the steps of determining the properties of the particular oil-bearing formation to be flooded, selecting an additive having predetermined adsorption and thermal properties and, when used to flood the formation, will significantly increase the amount of oil recovered over a conventional water flood, preparing a solution, suspension or emulsion of the additive in a concentration effective in increasing oil recovery from the formation, injecting the additive solution into the formation through one or more injection wells to establish an additive zone in the formation, and, following the injection of the additive solution, injecting through the same or nearby injection wells at least a slug of fluid at a predetermined elevated temperature to move the additive zone through the formation and recovering oil from one or more recovery wells.

It is an object of the present invention to provide a method of improving additive flooding by making predetermined temperature adjustments in either or both the additive solution and the drive water.

Further advantages and objects of the invention will become apparent from the following detailed description read in view of the accompanying drawings which are a part of this specification and in which:

FIGURE 1 shows Langmuir-type isotherms illustrating the influence of temperature and concentration on the adsorption of a typical additive at the internal surfaces of porous formation rock.

FIGURE 2 is a vertical section of an oil-bearing formation and is useful in illustrating one embodiment of the invention.

FIGURE 3 is a vertical section of an oil-bearing formation and is useful in illustrating one embodiment of the invention.

FIGURE 4 is a schematic diagram illustrating apparatus useful in demonstrating the present invention.

FIGURE 5 shows curves obtained from additive floods.

FIGURE 6 shows curves obtained from additive floods.

FIGURE 7 shows curves obtained from additive floods.

The amount of adsorption for a given additive used in water flooding is primarily dependent on three variables. These variables are the formation surface, the concentration of the additive in solution and the temperature of the solution when contacted with the formation. Referring to FIGURE 1, adsorption isotherms at temperature T_L (low) and at temperature T_H (high) are shown for a representative additive which may be used in the method of the invention. The term additive is meant to include surface-active agents including cationics, nonionics, anionics, and ampholytics, water thickeners, bactericides, chemical tracers, and any other additives to a flood which have adsorption isotherms generally similar to those of FIGURE 1 in that the adsorption at the higher temperature is less than at some preselected lower temperature.

If T_L is used to refer to the temperature of a given formation in which an additive flood is contemplated and T_H is used to represent the temperature of a heat bank which is to be established in the given formation according to the present invention, it is evident by examining the isotherms at T_H and T_L in FIGURE 1, that the weight of additive absorbed at the formation surface at the contemplated injection concentration is significantly less at T_H than for the same concentration at T_L . Thus when selecting an additive in accordance with the invention, consideration must be given to the adsorption characteristics of the additive at different temperature levels. Any additive which has isotherms similar to those shown in FIGURE 1 and which has the herein-described thermal and oil recovery properties is usable as an additive in an assisted recovery flood according to the present invention.

Since it is well known in the art that not all additives will economically increase the recovery of oil over a conventional water flood in all reservoirs, it is obvious that in selecting an additive for the flood, the first consideration must be to select a number of additives having properties which will economically increase oil recovery in the particular reservoir under consideration. The minimum concentration of additive which is effective in economically recovering oil is determined at this initial stage and, in addition, the maximum amount of additive which can be added to the solvent before gelling or precipitation occurs must be determined for the additives. These data can be obtained by conventional laboratory methods including core flooding carried out under simulated reservoir conditions of pressure, temperature and oil saturation.

After preliminarily selecting a number of additives with desired recovery properties, the adsorption properties of the additives at different temperatures must be determined. To find these properties, tests are conducted in the laboratory at various temperatures including at least the temperature of the formation (T_L) and at a temperature (T_H) which can be maintained in a heat bank in the reservoir. The temperature of the formation may be determined by any convenient method, such as lowering a temperature-responsive resistor disposed in a sinker into a well adjacent the producing formation. T_H may be the highest temperature which can economically be maintained in a heat bank in the formation and the preselected additives' thermal and adsorption properties determined at this temperature or the selection of T_H may be based on the above-obtained laboratory data for a number of different additives at various temperatures and T_H selected

equal to the temperature where a given additive has the most promising adsorptive and thermal properties. It has been found that any increase in temperature of the heat bank over the formation temperature is helpful in carrying out the invention. However, it is preferred to have at least a 10° F. temperature gradient between the formation and the thermal drive water. Thus, T_H should be at least 10° F. greater than the formation temperature. The upper limit of T_H is governed by the economics of maintaining the heat bank in the formation and the temperature at which a given additive selected for the flood thermally decomposes or precipitates. The concentration of the additive in solution during these adsorption tests is at least the minimum concentration which will produce increased oil recovery and preferably the concentration is the maximum concentration before gelling or precipitation occurs. Since it is well known that some additives change drastically in solubility when subjected to increased temperatures, this thermal property must be examined and if substantial precipitation occurs at T_H , then this additive must be eliminated from consideration. In addition, any additive which thermally decomposes at the expected T_H must not be selected for the flood. The amount of adsorption can be determined by conventional laboratory means, at different temperatures, and the additive with best adsorption properties selected. Here, it is desirable that not only the adsorption at T_L be relatively low, but also that the increment in the amount adsorbed between T_L and T_H be large. The additive which has the largest increment, other properties being equal (including low temperature adsorption), should be selected for the flood.

In preparing the additive solution for injection into the formation, consideration must be given to the laboratory tests heretofore described, particularly with regard to the minimum concentration effective in recovering additional oil and the maximum amount of additive that may be mixed with a given volume of water before gelling or precipitation occurs. The present method permits the use of a smaller amount of additive than was heretofore possible. Although additives obviously vary in properties, it is generally expected that utilizing the method of the present invention, a successful additive flood can be accomplished using between .02 pound/barrel of pore space of the flooded formation to 2 pounds/barrel of pore space of the flooded formation. In one embodiment of the invention, this additive is mixed with water in as concentrated a solution as possible, without causing gelling or precipitation, prior to injection into the formation. Mixing the additive in this manner reduces injection costs by lowering the volume of solution which must be injected, and it also provides for the establishment of a highly concentrated additive bank. The additive solution, however, may be injected in any volume in which the additive concentration does not fall below the minimum concentration effective in recovering increased oil.

With reference to FIGURE 2, apparatus for injecting and recovering fluids from an earth formation is shown. The methods of and apparatus for injecting liquids into a formation and recovering fluids from a formation are well known in the art and generally any of these may be utilized in the practice of the present invention. One form of apparatus for injecting fluids into a formation 1 includes a tubing string 30. The tubing string 30 communicates with the producing formation through appropriate pack-off means 32. The discharge end of a conventional pump 34 is connected to the other end of tubing string 30. Tubing means 35 are provided for flowing fluid, such as the additive solution to the pump 34. Heating means (not shown) are provided to increase the temperature of the injected fluids in accordance with the invention.

It has been found that when an additive solution is injected into a formation which has a temperature greater than atmospheric temperature, the manner in which the

injection is accomplished can be crucial to the success of the flood. More specifically, even when an additive selected for a given flood does not adsorb at a particular formation surface at the there-existing temperature to the extent that requires that the additive solution be followed by a heat bank, it has been found that if the contemplated injection temperature of the additive solution, which is normally atmospheric temperature, is less than about 10° F. less than the temperature of the formation, the additive solution will split into two fractions as it moves out into the formation by the injection of atmospheric temperature drive water. One fraction will move on out into the formation while the other fraction will be immediately adsorbed at the formation surface. Thus if there is a disparity of greater than about 10° F. between the additive solution and the hotter formation, splitting of the injected bank will result. The reason for this phenomenon is not known, but, because this splitting effect does occur in the additive bank, the concentration of the additive in solution in the bank is greatly reduced, usually to the place where it is no longer effective in recovering oil. While the fraction of additive immediately adsorbed may be desorbed by the later cold drive water, the beneficial effect of the concentrated slug of additive solution passing at one time is lost. It has been discovered that this undesirable effect can be avoided. One method of avoiding this result includes controlling the rate of the injection of the additive solution so that the solution takes advantage of the natural heat of the formation and is itself progressively heated to formation temperature as it is injected. Then if the additive is not too severely adsorbed, atmospheric temperature drive water may then be injected to push the additive bank through the formation without the above-described splitting occurring. Injection rates vary, obviously, on the particular thermal properties of a given reservoir. The most desirable rate of injection of the additive solution to take advantage of the heat present in a particular reservoir can be determined in tests on core samples of the formation run under simulated formation conditions. A method, not intended to limit the invention but rather as an aid in its application, of calculating an injection rate whereby the additive solution will enter the formation at substantially formation temperature is contained in an article entitled, "How To Calculate Temperature Profiles in a Water-Injection Well," by Jan Moss and Philip D. White; on page 174 of the Oil and Gas Journal, volume 57, No. 11, March 9, 1959.

Another method of injecting an additive solution into a formation in a manner that prevents splitting of the additive bank comprises determining the formation temperature and then raising the temperature of the additive solution at the surface of the earth to at least the temperature of the formation plus the calculated heat lost during injection. The hot additive solution is then injected into the formation at any convenient rate of injection. If the adsorption problem is not overly severe then atmospheric temperature drive water may be injected to force the additive bank through the formation. Generally speaking, formations in which this embodiment of the invention are practiced are elevated temperature formations wherein advantage may be taken of the natural heat of the formation in overcoming the adsorption problem. In this sense it should be explained that although an elevated temperature formation would normally be expected to be one in excess of 150 to 200° F., there are occasions where the additive solution should also be heated prior to injection in lower temperature reservoirs. This is especially true when the prevailing atmospheric temperature is much lower than formation temperature, as is the case in many northern areas. This is true because we have found that it is the temperature increment between the injected solu-

tion and the formation that is controlling and not the absolute temperature of the formation itself.

In accordance with the preferred embodiment of the invention an additive solution bank is established in a formation by injecting a predetermined amount of additive solution through one or more injection wells into the formation. After the additive solution has been injected into the formation and the additive bank thus established, at least a slug of hot water is injected through the same or other injection wells to set up a hot zone behind the additive bank and to move the additive bank through the formation. The hot water following the additive bank progressively desorbs additive which has been adsorbed on the rock surfaces and returns it to the additive bank. The concentration of the additive bank thus remains high and the time required to move the additive through the formation is greatly reduced.

With reference to FIGURE 2, a vertical section of an oil-bearing formation 1 penetrated by at least one injection well 7 and one recovery well 8 is shown. The unflooded portion of formation 1 is represented by numeral 2, the underlying strata by 10 and the overlying strata by 12. In one embodiment of the invention, an additive solution bank 3 is established in formation 1 by means of injecting an additive solution from the surface of the earth 5 through injection borehole 7 into the producing formation 1. The additive is selected and the solution prepared as heretofore described. The injection is accomplished by any conventional means and at any convenient rate. In this embodiment of the invention, the solution is injected into the formation at substantially atmospheric temperature. Following the injection of the additive solution, a thermal drive zone 4 is created by injecting hot water through borehole 7. The optimum temperature of this drive water depends on the variable previously discussed. However, we have found that a temperature increase of at least 10° F. over the formation temperature is generally the smallest increment with which to successfully practice the invention. The injection of the hot water is continued until the additive zone 3 is moved substantially through producing formation 1. Products of the drive are recovered through borehole 8 by means, for example, of a production pump 29 and tubing 40. The injection water may be heated by any conventional means such as a boiler on the surface of the earth. However, the invention is not dependent on the method of heating the water. Drive water could, for instance, be heated by passing it through a heat bank established by underground combustion, either prior to or following the injection of the additive solution in formation 1.

An alternative embodiment of the invention is illustrated in FIGURE 3. FIGURE 3 is a vertical section of an oil-bearing formation 25, overlying strata 26, underlying strata 27, at least one injection well 17 and at least one recovery well 18. An additive bank 21 is established in formation 25 by injecting as heretofore described an amount of additive solution. The additive bank 21 is moved into the formation 25 by means of a hot water slug 22 injected through well 17 which in turn has been followed by atmospheric temperature drive water 23 also injected through well 17. The portion of the formation which has not yet been subjected to the additive flood is represented by numeral 20. It is recognized that in actual field practice a number of wells probably would be used as injection wells. The method of this invention therefore is not limited to any unique arrangement of wells.

In this embodiment of the invention, a preselected additive is added to water or other suitable carrying agent in the manner heretofore described and the solution is injected into formation 25 from the surface 15 at substantially atmospheric temperature and at any convenient injection rate. Following the establishment of the additive

zone 21, a slug of elevated temperature water is injected through borehole 17 into formation 25 to move the additive zone 21 out into the formation 25. For most formations a hot water slug between .1 pore volume to .6 pore volume is preferred. In most applications the slug of hot water should be initially injected at as high a temperature that can be maintained without causing thermal decomposition or precipitation of the additive used in the flooding solution. However, any temperature increase in the slug of water over the temperature of the formation is beneficial to the flood and may be utilized in this method. After the slug of hot water has been injected, atmospheric temperature water may be used to move the additive bank 21 and hot water slug 22 substantially through reservoir 25 to oil production well 18 where the products of the drive are produced.

While the method of the invention has been described in a system including an injection well and a production well it is clear that the method may also be advantageously used in a single well system. For example, it is often desired to contact the oil around a well with an additive and then to back-flow this oil into the same well for production therefrom. Thus a cold additive solution, containing for example an additive which will reduce the viscosity of the oil, is injected into a well. Hot drive water or steam is injected for a predetermined time through the same well to move the additive solution out into the formation without great loss by adsorption. The hot water or steam injection is then stopped and the well produced.

A number of demonstrations have been made to show the advantages of the method of the present invention. The apparatus used in the demonstrations is shown schematically in FIGURE 4. A glass column 50 was packed with crushed sandstone 51 to simulate an oil-producing formation. Each of the ends 52 and 53 of the glass column were filled for a short distance with small glass beads. The length of the glass column was about 183 centimeters. About 161 centimeters of the column was packed with sand. When packed with sand the pore volume of the sand pack in the glass column 50 was about 80 cubic centimeters. Runs using both Berea sandstone and Torpedo sandstone were made. The porosity of the packed sand in glass column 50 was 39% and the permeability was 1.47 Darcies when Berea sandstone was used and the porosity of the packed sand was 27 to 40% and the permeability about 2.74 Darcies when Torpedo sandstone was used.

One end 54 of the glass column 50 was prepared with suitable tubing 55 and 56 for connection with a water injection pump 57 and an additive solution injection pump 58. Valves 59 and 60 were provided to control the flow of water and additive solution into the glass column 50. The other end 61 of the glass column 50 was provided with a drain tube 62 and a means 63 for collecting fluid flowing therefrom. A movable electric furnace 64 was arranged around the outside of the glass column 50 to simulate a heat bank in a producing formation. The furnace was movable along the column. A thermocouple 65 connected to a temperature recorder 66 provided temperature information along the column.

Using the demonstration apparatus shown in FIGURE 4 runs simulating an additive fluid without benefit of a heat bank could be made simply by not using the furnace. When the furnace was heated and moved down the glass column it simulated the movement of a heat bank moving through the formation. Thus comparative data were collected, which data show the advantages of the present invention.

Demonstration I

With reference now to FIGURE 5, the results of a demonstration are graphically shown by means of a pair of curves. A water thickener or viscosity builder was the additive used in the demonstrations illustrated in FIG-

URE 5. The specific additive was CMC4-L manufactured by The Hercules Powder Company. CMC4-L is a trademark of the Hercules Powder Company and is a carboxymethyl cellulose polymer having the general formula

where R represents the cellulose chain. The additive is a white granular powder having no odor and is anionic. Low concentrations of the additive in water produce a viscous solution. These viscous solutions provide improved oil recovery from a petroleum-bearing formation by providing a more favorable water-oil mobility ratio. Oil recovery is more efficient when the viscosity of the pushing fluid approaches the viscosity of the pushed oil.

A CMC4-L solution having a viscosity of 10.9 cp. was prepared. The solution was made in brine having 17 gm. of NaCl per liter. The glass column packed with crushed Berea sandstone as described above was first prepared by saturating it with brine. The additive solution was then injected into the column to set up an additive bank in the column. The slug size of the additive bank was about .151 pore volume. After the additive bank was established in the column, room temperature brine (about 22° C.) was injected into the column to move the additive bank through the column while samples of the effluent from the column were continuously taken. The viscosity of the effluent was measured and is plotted as a function of the effluent volume in the curves in FIGURE 5. The first peak in the solid curve represents the additive in the effluent moved through the formation by room temperature brine. As is evident by the curve, the additive solution began to appear in the effluent after about one pore volume of brine had passed through the glass column. Additive continued to be evidenced in the effluent during injection of the next half pore volume of brine. The brine injection was continued until about three total pore volumes of brine had passed through the column. It is apparent from the curve that very little additional additive was carried through the glass column by the continual flow of brine.

After the three pore volumes of brine had passed through the column, the furnace was positioned at the entering end of the column, and the temperature of the furnace was raised to about 85° C. The furnace was started down the column after about 3.1 pore volumes of effluent had emerged from the downstream end of the column. The furnace was moved slowly down the column toward the outlet in a manner to simulate the movement of a heat bank through the formation. The furnace traveled at approximately 75% of the fluid velocity. The second peak in the solid curve of FIGURE 5 shows the additional additive in the effluent which was desorbed from the porous sand and moved through the formation by the injection of a small additional amount of water. The additional additive is reflected by the peak effluent viscosity shown in the right-hand portion of the solid curve at 4.0 to 4.5 pore volumes effluent. The heat bank and the increased velocity solution apparently traveled together down the column.

Demonstration II

The method of the invention is even more dramatically demonstrated by a further demonstration carried out in a column packed and arranged in the same manner as the one described above. An additive solution of CMC4-L having the same properties as the solution described above was prepared and injected into a column prepared as described in the above demonstration. The slug size of the solution was again about .151 pore volume. About 0.18 pore volume of flush water was injected. The furnace was then placed at the inlet end of the column and the temperature raised to 85° C. The furnace was started after the 0.18 pore volume of drive water had been in-

jected behind the additive bank. The furnace was then slowly moved along the column while flush water was injected. The furnace traveled at approximately 83% of the speed of the fluid. The dashed curve of FIGURE 5 illustrates the effect of the thermal bank moving through the formation with the additive bank. The additive bank remained well defined and a great deal more additive stayed in solution as is witnessed by the greatly increased viscosity of the effluent. It is also apparent that the additive bank passed through the column when less than 1.5 pore volumes of effluent were collected. As is shown, additional flushing water did not bring any additional additive through the column. This demonstration shows clearly the improved oil recovery that can be obtained using the method of the present invention to both maintain maximum additive in solution and to require the least amount of drive water to move the additive bank through the formation.

Demonstration III

With reference now to FIGURE 6, the results of another demonstration are graphically shown. A surfactant was the additive used in the demonstration illustrated in FIGURE 6. The additive was a California Research Corporation Special Alkane Sulfonate 10B-R. The surfactant was made by sulfonating the alkyl benzenes from the heavy fraction of an El Segundo polymer. The resulting material has a molecular weight of about 35 units greater than the regular "alkane." The empirical formula is

Thus the surfactant is anionic. An .11 wt. percent solution of the alkane sulfonate was prepared with distilled water. A slug of the solution in the amount of .154 pore volume was then injected into a glass column similar to the one shown in FIGURE 4. The column was packed with Torpedo sandstone.

After the slug was injected into the column, room temperature water (about 22° C.) was injected to attempt to drive the surfactant through the formation. As illustrated in the curve of FIGURE 6, a very small concentration of surfactant emerged from the column at from 1.2 to 1.5 effluent pore volumes. This amount represented only about 6 percent of the weight of the surfactant originally injected. It is noted that even this small amount of surfactant was held back by adsorption since it did not begin to emerge from the column until 1.2 pore volumes of effluent appeared. Continued room temperature water injection produced no more surfactant.

After 1.21 pore volumes of effluent had appeared at the downstream end of the column the furnace was started at the upstream end of the column and moved along the column at .83 times the velocity of the water moving through the column. The furnace temperature was 85° C. and produced a heat bank in the formation in accordance with the present invention.

Again referring to FIGURE 6 the second peak of the curve illustrates the arrival of the surfactant bank at the downstream end of the column. The surfactant, illustrated by the peak, emerged just before the furnace reached the downstream end of the column. In this respect the concentration of the alkane sulfonate in the surfactant bank at the end of the column was about .20 wt. percent while the concentration of the alkane sulfonate in the original injection slug was only .11 wt. percent. Thus the concentration of the surfactant in the effluent was almost twice the concentration of the surfactant in the original injected slug. This illustrates that a heat bank following the additive bank can actually cause the concentration of the additive in the bank to exceed even the concentration of additive in the original slug. This is obviously of a great advantage in oil recovery.

ery since the greater concentration of the additive reaching the oil, the better the recovery will be.

Demonstration IV

Referring now to FIGURE 7 the results of another demonstration are graphically shown by a pair of curves. A surfactant solution was prepared using Ninol 1281. Ninol 1281 is a trademark of the Stephan Chemical Company, Maywood, New Jersey. Ninol 1281 is nonionic and is a fatty acid alkylamide with the empirical formula

where R is the alkyl chain(s) occurring in coconut oil; where R' and R'' are the alkyl chain(s) of simple alcohol and generally R' is identical with R''.

A .10 percent by weight concentration solution of the surfactant was prepared in distilled water and a .15 pore volume slug was injected into a column similar to the one shown in FIGURE 4 filled with Torpedo sandstone. The slug of the surfactant was followed by room temperature (about 22° C.) distilled water. Samples of the effluent were collected and analyzed. The solid curve in FIGURE 7 illustrates the concentration of the surfactant in the effluent from the column.

For comparative purposes an identical surfactant solution was prepared and an identical slug of surfactant was injected into the upstream end of an identically prepared column. Drive water was injected behind the surfactant. The furnace was turned on and reached a temperature of 80° C. The furnace was started after .17 pore volume of distilled drive water had been injected into the column. The heat bank was moved down the column at about .80 times the velocity of the water traveling through the column. The furnace reached the end of the column at approximately 1.43 pore volumes effluent. The dashed curve in FIGURE 7 shows the concentration of the surfactant versus the effluent volume. As is apparent by comparing the two curves, a much higher concentration of the surfactant was moved through the formation using the heat bank in accordance with the invention. Also much less water was required to move the additive solution through the formation using the heat bank.

The above demonstrations illustrate the advantages of the method of the present invention both in maintaining maximum additive in solution and in requiring the least amount of drive water to move the additive bank through the solution.

It is apparent that modifications other than those described herein may be made to the method of this invention without departing from the inventive concept. It is intended that the invention embrace all equivalents within the scope of the appended claims.

We claim:

1. The method of improving oil recovery from a petroleum-bearing formation which comprises determining the formation temperature, mixing an additive with pre-selected thermal, adsorption, and recovery properties with a liquid, said additive selected from the group consisting of nonionic surface active agents, anionic surface active agents and water thickeners, injecting said liquid containing said additive into said formation, following said liquid containing said additive injecting a hot drive liquid into said formation at a temperature higher than said formation temperature and the temperature of said liquid containing said additive to create a temperature gradient of at least about 10° F. between said drive liquid and said liquid containing said additive, continuing the injection of said drive liquid to force said liquid containing said additive out into said formation and recovering oil from said formation through a well.
2. The method of improving oil recovery from a pe-

petroleum-bearing formation which comprises determining formation temperature, mixing an additive with preselected thermal, adsorption, and recovery properties with a liquid, said additive selected from the group consisting of nonionic surface active agents, anionic surface active agents and water thickeners, injecting said liquid containing said additive into said formation, following said liquid containing said additive injecting a hot drive liquid into said formation at a temperature higher than said formation temperature and the temperature of said liquid containing said additive to create a temperature gradient between said drive liquid and said liquid containing said additive, continuing the injection of said drive liquid to force said liquid containing said additive substantially through said formation toward a producing well and recovering oil from said formation through said producing well.

3. The method of claim 2 where the said temperature gradient is at least about 10° F.

4. The method of claim 2 where the said temperature gradient is at least about 60° C.

5. The method of improving oil recovery from a petroleum-bearing formation which comprises determining said formation temperature, mixing an additive having predetermined thermal, adsorptive and oil recovery properties with a liquid, said additive selected from the group consisting of nonionic surface active agents, anionic surface active agents and water thickeners, injecting said liquid containing said additive into said formation to form an additive bank in said formation, following said liquid containing said additive by a slug of drive liquid in an amount between 0.1 and 0.6 pore volume of said formation injected into said formation at a temperature higher than said formation temperature to create a temperature gradient between said drive liquid and said liquid containing said additive, said drive liquid having a temperature high enough to maintain said temperature gradient after heat exchange with said additive liquid, following said drive liquid injecting water into said formation at substantially atmospheric temperature to substantially move said additive bank and said drive liquid through said formation and recovering oil from said formation.

6. The method of claim 5 wherein the additive is contained in the liquid in an amount between .02 pound per barrel of formation pore space and 2 pounds per barrel of formation pore space, there being sufficient liquid to prevent gelling or precipitation of said additive, and the temperature gradient between the drive liquid and the said liquid containing said additive is at least 10° F.

7. The method of improving oil recovery from a petroleum-bearing formation, said formation having a known temperature comprising selecting an additive which will increase oil recovery from said formation, said additive being less adsorbed at said formation surface at a temperature above said known formation temperature than at said formation temperature, said additive selected from the group consisting of nonionic surface ac-

tive agents, anionic surface active agents and water thickeners, injecting into said formation a liquid containing said additive at substantially atmospheric temperature, injecting between 0.1 and 0.6 pore volume of drive liquid into said formation at a temperature at least 10° F. greater than said formation temperature, following said drive liquid injecting water at substantially atmospheric temperature into said formation to substantially move said liquid containing said additive through said formation and recovering oil from said formation.

8. The method of improving the recovery of petroleum from a petroleum-bearing formation penetrated by at least one injection well and one recovery well, said formation having a known temperature comprising establishing in said formation adjacent said injection well a solution containing an additive, said additive selected from the group consisting of nonionic surface active agents, anionic surface active agents and water thickeners, said additive being less adsorbed at said formation surface at temperature T_H than at temperature T_L , where T_H is a temperature at least 10° F. higher than said formation temperature and T_L is the temperature of said petroleum-bearing formation, injecting a drive liquid into said formation through said injection well to move said additive solution out into said formation, said drive liquid having a temperature at least equal to T_H , continuing the injection of said drive liquid to force said additive solution substantially through said formation and recovering petroleum from said formation through said recovery well.

9. In a method of improving the recovery of oil from a petroleum-bearing formation which method includes the step of injecting an additive solution through an injection well to establish an additive solution bank in the formation, the improvement comprising selecting an additive from the group consisting of nonionic surface active agents, anionic surface active agents and water thickeners for use in forming an additive solution for injection through an injection well to form an additive solution bank in a formation and injecting a drive liquid into said formation through said injection well to move said additive solution bank through said formation, said drive liquid having a temperature of at least about 10° F. higher than said formation temperature and the temperature of the additive solution to establish a temperature gradient between said drive liquid and the additive solution bank in said formation.
